UNITED STATES PATENT OFFICE.

CARRIE M. DRAPER, OF NEWTON HIGHLANDS, MASSACHUSETTS.

DESIGN FOR A SOFA-PILLOW COVER.

SPECIFICATION forming part of Design No. 36,483, dated August 4, 1903.

Application filed April 13, 1903. Serial No. 152,483. Term of patent 3½ years.

To all whom it may concern:

Be it known that I, CARRIE M. DRAPER, a citizen of the United States, residing at Newton Highlands, in the county of Middlesex and State of Massachusetts, have invented a new, original, and ornamental Design for a Sofa-Pillow Cover, reference being had to the accompanying drawing, which represents a plan view of a sofa-pillow cover, showing my new design.

What I claim is—

The ornamental design for a sofa-pillow cover, as herein shown.

In testimony whereof I have affixed my signature in presence of two witnesses.

CARRIE M. DRAPER.
